H. R. TAYLOR.
FURNITURE DRAWER.

No. 20,100.

Patented Apr. 27, 1858.

UNITED STATES PATENT OFFICE.

H. R. TAYLOR, OF ROXBURY, MASSACHUSETTS.

DRAWER FOR CLOSETS, BUREAUS, &c.

Specification of Letters Patent No. 20,100, dated April 27, 1858.

To all whom it may concern:

Be it known that I, HENRY R. TAYLOR, of Roxbury, in the county of Norfolk and State of Massachusetts, have invented certain new and useful Improvements in Drawers for Closets, Furniture, &c., of which the following is a full, clear, and exact description, reference being had to the accompanying drawings, making part of this specification, in which—

Figure 1 is a plan of a bureau with the drawers pulled out. Fig. 2 is a vertical section of the same on the line x, x , of Fig. 1.

In bureau and other drawers it is found that when they contain articles of much weight, they cannot be pulled out to near their full extent without danger of the drawer sagging down so as to injure the article of furniture, and also to make it difficult to push the drawer back again into place. And when a drawer is of considerable width on the front without a corresponding depth, it is liable to push in unequally or with the sides of the drawer out of parallel with the sides of its receptacle. To obviate these difficulties is the object of my present invention which consists in supporting the drawer when pulled out in a manner substantially such as will now be described.

In the drawings A, represents a bureau having one drawer B, which is pulled out to its full extent, the drawer is supported when drawn out, in the following manner: A sliding piece C, of the form shown in Fig. 2 is placed alongside of the drawer on each side of it; a cleat D, Fig. 2 is attached to the inside of the bureau immediately above the path of the piece C, and of a corresponding thickness so as not to interfere with the drawer when the latter is pushed in, a groove a , in the lower edge of this cleat receives a tongue b , on the upper edge of the piece C, as this groove is not cut the whole length of the cleat but stops at c , the piece C cannot be drawn out beyond the position shown in Fig. 2, a portion of the side of the groove a is cut away at the rear end at d to admit the tongue b , when the piece C, is entered in its place.

The drawer has attached to each side a roller f , that is supported in a metal box or band e , this roller runs on the edge of the

piece C, at a part of it which is cut down, leaving a shoulder at g against which the box e , strikes when the drawer is pushed in, and another shoulder at h against which the box e , strikes when the drawer is pulled out.

In large drawers I make use of friction rollers k , and l , (shown dotted) which are placed beneath the drawer, but as these are not essential to the working of the parts they need not be further described. Instead of the box e , and roller f , a single stop of hard wood may be attached to the side 65 of the drawer.

The following is the way in which this drawer operates. As the drawer B, is pulled out the metal boxes e , strike against the shoulders h , and draw out the sliding pieces 70 C, the tongue b , running in the groove a , prevents any lateral vibration of the pieces C, and they in turn keep the drawer straight. When the drawer is out it is effectually supported by the rollers f , resting on the pieces 75 C and these being drawn out but part way are supported in the bureau between the bottom E, over which the drawer slides and the cleats D, above them. As the drawer is pushed in the boxes e , strike the shoulders g , 80 and carry the pieces C in with the drawer, when they are entirely concealed by the projections m , on the front of the drawer.

With a drawer arranged and supported as above described, it may be pulled out to its 85 full extent without danger of its falling out of its recess or of sagging down, and in returning it into its place it will not be requisite to lift the weight of the front part before it can be pushed in while the pieces 90 C, serve as guides for the sides of the drawer and prevent the lateral motion which makes the drawer bind first on one side and then on the other when not pushed in straight.

I have spoken of this improved method 95 of supporting drawers as applied to bureaus, but it is evident that it may be used for almost every kind of drawer and is particularly useful where it is intended to contain articles of much weight.

It is obvious that there are other plans of carrying out my invention without departing from the spirit of it; for instance a piece somewhat wider than the bottom of the drawer may be arranged beneath it, to 105 be pulled out with the drawer in a similar

manner, small cleats at the side of the receptacle preventing the piece from being tilted; but the plan first described is that which I prefer.

5 What I claim as my invention and desire to secure by Letters Patent is—
The sliding pieces C, or their equivalents

connected with the drawer and operating in the manner substantially as herein set forth.

HENRY R. TAYLOR.
